M. Talbert Dick

UNITED STATES PATENT OFFICE

2,366,000

COMPASS

Edwin G. Brockman, Indianola, Iowa

Application September 29, 1941, Serial No. 412,793

4 Claims. (Cl. 33—152)

The principal object of this invention is to provide a relatively flat combination compass, ruler and protractor.

A further object of this invention is to provide a compass that may be easily carried in a book or in the vest pocket of the user.

A still further object of this invention is to provide a new and novel method of detachably and adjustably securing the lead in a compass.

A still further object of my invention is to provide a combination compass, protractor and ruler that is economical in manufacture and durable in use.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawing, in which:

Fig. 1 is a side view of my device ready for use.

Fig. 2 is a side view of my device showing its other side.

Fig. 3 is an enlarged cross sectional view of my device taken on line 3—3 of Fig. 1.

Fig. 4 is an enlarged view of one of the ends of the compass that holds the lead and more fully illustrates its construction.

Fig. 5 is a top plan view of my compass.

Compasses are very old. The usual compass, however, has relatively large arms circular in cross section and with various protruding knobs and like. Such compasses cannot be easily or successfully carried in the pocket or placed and carried within the covers of a book without distorting and damaging the book. I have overcome such objections by providing a simple and substantially flat compass.

Referring to the drawing, I have used the numerals 10 and 11 to designate the two arm portions of my compass. These two arm portions are hingedly secured together at their top and are operatively connected to the usual handle portion 12 as shown in Fig. 1. These arms 10 and 11 are of flat construction as shown in Fig. 5 and may be made of any suitable material such as Bakelite or like. The arm 11 has its outer marginal edge straight and marked as a ruler 13 as shown in Fig. 1. On the other side of the two arms 10 and 11 I have marked a protractor 14 as shown in Fig. 2. The numeral 15 designates the usual centering needle protruding from the lower end of the arm 11. The numeral 16

designates a longitudinal slot opening in the lower end portion of the arm 10. The central portion of each of the walls of this slot is concave in cross section as shown in Fig. 3 to receive and partially embrace the lead 17. The numeral 18 designates a metallic handle sleeve having its two ends pivoted by the rivet 19 extending through the lower portion of the arm 10 at one side of the slot 16 and with its central portion loosely embracing and extending around the opposite end portion of the arm 10 as shown in Fig. 3 and Fig. 4. The numeral 20 designates a cam slot in each side of the member 18. The numeral 21 designates a pin or like in each side of the arm 10 capable of being engaged by the two cam slots 20 as shown in Fig. 3. These pins 21 are located in the end portion of the arm 10 opposite from that portion of the arm carrying the rivet 19. By this arrangement when the member 18 is manually moved outwardly and as shown in Fig. 4 the pins 21 will be free of the cam slots 20. When the sleeve lever 18 is moved downwardly on and around the lower portion of the arm 10 as shown by dotted lines in Fig. 2, the cam slots of this member will engage the pins 21 and thereby bring the two forked end portions of the arm 10 together to tightly clamp and engage the lead 17. This member 18 is of relatively thin material and provides a relatively smooth surface as a fastening means for the compass. This lead tightening means does not effect the flat character of the compass and eliminates necessity of knobs, screws, bolts and like usually found in compasses. When the member 18 is in open condition, the lead 17 may be manually slid inwardly or outwardly relative to the slot 16. After the lead has been properly adjusted, it is merely necessary to close the member 18, thereby tightly clamping the lead 17 in place.

Some changes may be made in the construction and arrangement of my improved substantially flat combination compass, ruler and protractor without departing from the real spirit and purpose of my invention, and it is my intention to cover by my claims any modified forms of structure or use of mechanical equivalents which may be reasonably included within their scope.

50 I claim:

1. In a device of the class described, two elongated arms each having a relatively large width relative to their thickness, a means for hingedly securing said two arms together, a pointed element extending from the free end of one of

said arms, a slot in the end of said other arm, a marking element slidably adjustably positioned within said slot, a handle member pivoted to said last mentioned arm and at one side of said slot, a circular cam slot in said handle member, and a projection on said last mentioned handle member capable of being engaged by said cam slot when said handle member is moved in one direction.

2. In a device of the type described including a leg member, a channel extending upwardly adjacent the lower end of said leg adapted to receive a marking element and adapted also to have the size of its cross section varied, a member pivotally mounted on said leg adjacent said channel, a cam slot in said pivotally mounted member and a protuberance on said leg adjacent said channel adapted to at times engage said cam slot to reduce the cross section of said channel.

3. In a device of the type described including a leg, a channel extending upwardly adjacent the lower end of said leg adapted to receive a writing element and adapted also to have the size of its

cross section varied, a bifurcated member having the extended ends of its arms pivotally mounted on said leg to one side of said channel, protuberances on each side of said leg on the other side of said channel, cam slots in the arms of said bifurcated member adapted to engage said protuberances to reduce the cross section of said channel and means for manipulating said bifurcated member.

4. In a device of the type described a pair of leg members pivotally united adjacent their tops, a pointer element adjacent the lower end of one leg, a channel extending upwardly adjacent the lower end of the second leg, said channel being adapted to receive a writing element and capable of having the size of its cross section varied, a member pivotally mounted on said second leg adjacent said channel, a protuberance on said second leg adjacent said channel, and a cam slot in said pivoted member adapted to engage said protuberance to reduce the cross section of said channel.

EDWIN G. BROCKMAN.
